(57) **CLAIM**

(73) Assignee: **LightSurf Technologies, Inc., Santa
Cruz, CA (US)**

The ornamental design for a vertically-oriented digital cam-
era body with connector interface, as shown and described.

(**) Term: **14 Years**

DESCRIPTION

(21) Appl. No.: **29/126,738**

The present application is related to the following com-
monly-owned applications: (1) Application Ser. No. 29/126,
740, filed concurrently, and titled, Vertically-Oriented Digital
Camera Body with Lens Assembly Reveal; (2) Application Ser. No. 29/126,739, filed concurrently, and
titled, Vertically-Oriented Digital Camera Body with Top-
Centered Shutter Button; and (3) Application Ser. No.
29/126,737, filed concurrently, and titled, Digital Camera
Viewfinder with Graphic Display. The disclosure of the
foregoing are hereby incorporated by reference.

(22) Filed: **Jul. 21, 2000**

FIG. 1 is a top, left and front perspective view of a
vertically-oriented digital camera body with connector inter-
face, the broken lines are shown to illustrate environment
only and form no part of the claimed design;

(51) LOC (7) Cl. **16-01**

FIG. 2 is a top, right, and front perspective view thereof;

(52) U.S. Cl. **D16/200**

FIG. 3 is a front end view thereof;

(58) Field of Search D16/200, 202,

FIG. 4 is a rear end view thereof; and,

D16/203–205, 208, 218, 219, 237; 348/373–376,
838; 396/535–541

FIG. 5 is a bottom, left, and front perspective view thereof.
